SHOULDER SHAPING PAD

Edward James Hoffman, Bremerton, Wash.

Application January 29, 1934, Serial No. 708,762

4 Claims. (Cl. 223—17)

This invention relates to improvements in shoulder shaping pads of that character used in the pressing of coats; the principal object of the invention being to provide a pad that may be easily and quickly applied to the shoulder portion of coats of various size and which will automatically adjust itself to proper size to shape and smooth out the shoulder portion for the steaming operation.

It is also an object of the invention to provide a pad of the above stated character that need not be readjusted for the completion of any pressing operation and may be left in place to retain the shoulder in shape while the material dries after steaming and pressing.

More specifically stated, the invention resides in the provision of a steaming and shoulder shaping pad comprising a plurality of independent pad sections and a bowed spring of a form and character whereby the pad will be expanded to fit the shoulder to which it is applied, but which permits the pad to be compressed for easy application and to accommodate itself to coats of different size.

Other objects of the invention reside in the details of construction and combination of parts as will hereinafter be fully described.

In accomplishing these and other objects, I have provided the improved details of construction, the preferred forms of which are illustrated in the accompanying drawing, wherein—

Fig. 1 is a face view of the pad, as expanded to full size.

Fig. 2 is a cross section of the pad, as seen along the line 2—2 in Fig. 1.

Fig. 3 is a cross section, as seen on line 3—3 in Fig. 1.

Fig. 4 is a view illustrating the device as applied to the sleeve and shoulder of a coat.

Fig. 5 is a perspective view illustrating an easy way of holding the device for its application to a coat.

Referring more in detail to the drawing—

Explanatory to the invention, it will be stated that the usual form of pad used in pressing coats is a single piece pad slightly larger than the hand. It is held by one hand of the operator within the shoulder portion of a coat and the coat is pressed thereby against the steaming board. The small size of the pad requires several readjustments of the coat thereon to complete the steaming operation, then the pad is removed and the coat placed on a hanger to dry. Since the steam applied for this operation leaves the material of the coat slightly damp, it is rather difficult to prevent the shoulder from becoming

wrinkled before it has an opportunity of drying unless some means is provided to hold it in shape.

The shoulder shaping pad of the present invention is designated in its entirety by reference numeral 1, and it is of U-shape and of a size adapted to fit within the upper portion of the sleeve of a coat with the rounded or base end thereof fitted to the shoulder seam as is shown in Fig. 4.

The body portion of the pad preferably is made of canvas, or a similar suitable material and is padded, with material of a suitable character, to a desired thickness. About its edges it is provided with a hem 2 in which a length of spring cable 3 is contained. The tendency of this cable is to straighten out and this yieldingly holds the pad at its maximum width.

The body of the pad is composed of three sections, comprising a base section 5 extending across the rounded base end to fill in about one fourth of the area. Extending from this base portion to the expandible end of the pad along its opposite sides are pad sections 6 and 6'. These latter sections are in the form of similarly shaped ears, free of each other but overlapping 25 to permit expansion of the pad to its full width without leaving any open space between the ears. The disconnected relation of the ears relative to each other also permits the pad to be compressed for easy application. The inner end portions of 30 the ear sections 6 and 6' overlap opposite sides of the end section 5 as is shown in Fig. 2 to close the inner end of the pad.

The spread of the pad at its open end under influence of the spring 3 is limited by a flexible 35 tie strap 8 that is extended across the open end and at its ends is sewed or otherwise attached to the ears 6 and 6' as indicated at 9 and 10 in Figs. 1 and 3.

The padding 13, as applied to the several sections, is tapered to the overlapping edges so that the overlapped parts form no abrupt ridge that would be detrimental to the pressing operation.

In using the device it is applied within the sleeve and shoulder as shown in Fig. 4; an easy 45 method of application being that illustrated in Fig. 5 wherein the pad is shown as overlying the right forearm of the one applying it, while he holds the open end of the pad retracted by gripping it with the right hand. The coat is held in 50 the left hand in position that the pad may be inserted into the sleeve from the upper end. In this way the pad may be inserted to the proper position, then when released will expand to draw the material of the sleeve and shoulder smooth 55

and with the rounded end of the pad seated against the shoulder seam, the shoulder will be shaped and smoothed for steaming.

The advantage of this pad is that it may be easily and readily applied and will automatically adjust itself to size. After once being applied it requires no readjustment during a pressing operation, and may be left in place to hold the garment in shape while it dries.

10 Pads of this character may be made in different sizes if so desired, and of various materials and the separate sections might be altered in proportion without departing from the spirit of the invention.

15 Having thus described my invention, what I claim as new therein and desire to secure by Letters Patent is—

1. A shoulder shaping pad adapted to be applied within the upper portion of the sleeve of a coat and comprising overlapping sections and having a rounded end adapted to seat against the shoulder seam to shape the shoulder portion of the coat thereto and a spring enclosed within the peripheral portion of the pad for causing it to expand laterally to smooth out the material of the sleeve enclosing it.

2. A shoulder shaping pad of the character described adapted to be inserted within the upper

portion of the sleeve of a coat; said pad being of U-shaped outline and made up of overlapping sections enclosing therein, about its sides and rounded end, a spring like bar having a tendency to straighten out and thereby to expand the pad laterally to smooth out the sleeve portion in which it is contained and to cause the rounded end to conform to the rounded shape of the shoulder.

3. A device as in claim 2 wherein the pad is composed of a plurality of sections with overlapping edges permitting expansion and contraction of the device, and means being provided for limiting the extent of expansion.

4. A shoulder shaping pad of the character described adapted to be inserted within the upper arm portion of a coat or the like; said pad being of U-shaped outline and enclosing therein about its sides and rounded end a spring like bar having a tendency to straighten out thereby to expand the pad laterally; said pad being composed of a pad section across the base end and opposite side pads extended in overlapped relation and also overlapping opposite sides of the base pad, and a tie strap joining the opposite side pads across the open end of the pad to limit the extent of expansion.

EDWARD JAMES HOFFMAN.
